UNITED STATES PATENT OFFICE.

JAMES B. BURKS, OF HOUSTON, TEXAS.

ENGINE.

Application filed September 12, 1921. Serial No. 499,885.

To all whom it may concern:

Be it known that I, JAMES B. BURKS, a citizen of the United States, residing at Houston, in the county of Harris and State 5 of Texas, have invented certain new and useful Improvements in an Engine, of which the following is a specification.

This invention relates to new and useful improvements in an engine.

One object of the invention is to provide 10 an engine of the character described, especially adapted for use on boats and other water craft, and which is of simple construction, is made of few parts, and is easily controlled.

Another object is to provide an engine of 15 the character described adapted for the use of steam as a motive power and equipped with a novel form of valve for the application thereof.

With the above and other objects in view, this invention has particular relation to certain novel features of construction, operation and arrangement of parts, an example 20 of which is given in this specification and illustrated in the accompanying drawings, wherein:—

Figure 1 is a longitudinal vertical sectional view of the engine.

Figure 2 is an enlarged longitudinal vertical sectional view of the controlling valve and adjacent parts.

Figure 3 is a vertical sectional view thereof, taken on the line 3—3 of Figure 2.

Figure 4 shows a side view of the valve sleeve.

Figure 5 is an end view thereof.

Figure 6 is a longitudinal vertical sectional view of another form of the engine.

Figure 7 is an enlarged longitudinal vertical sectional view of the valve employed in this form.

Figure 8 is a vertical sectional view thereof, taken on the line 8—8 of Figure 7.

Figures 9 and 10 show side and end views, respectively, of the valve sleeve employed in this form, and

Figure 11 shows an end view of this form of the engine.

Referring more particularly to the drawing, the numeral 1 designates the base on which the cylinder block 2 is mounted. This block, as shown, has three cylinders, 3, 4, and 5. In these cylinders the pistons 6 work, each piston being connected to the crank shaft 8 by means of the usual con-

necting rods 7. The crank shaft is rotatably mounted in suitable bearings in the engine base 1 and one end thereof is formed to be connected to the work to be driven. The 60 other end of this shaft is connected to a rotary valve 9, surrounding which there is a valve sleeve 10, slidably mounted in the casting 11 mounted on the base 1. The outer end of the sleeve 10 has the link 12 pivoted thereto at one end and the other end of this link is pivoted to the manual lever 13. This lever may be secured in any position desired by means of the usual rock-and-dog arrangement 14.

The valve 9 has the form of a hollow cylinder with both ends closed. At opposite ends it has the annular peripheral grooves 15 and 16, the former of which communicates with the interior of the valve through the ports 17, and the latter of which connects with a spiralled groove 18, in the valve 9. An inlet steam line 19 is connected into the valve casing 11, opposite the groove 15, and an exhaust steam line 20 is connected into 80 said casing opposite groove 16. The sleeve 10 has the oblong inlet and exhaust ports 21 and 22 arranged to register with said inlet and exhaust lines.

The sleeve 10 also has the outwardly tapering forward ports 23, 24 and 25, and reverse ports 26, 27 and 28, arranged in staggered relation, as shown in Figure 4.

The valve 9 has the steam ports 29, 30 and 31, arranged 120° apart and located so as 90 to successively register with the steam pipes 32, 33 and 34 respectively, as said valve rotates. These pipes lead from the valve casing and enter the expansion chambers of the respective cylinders 3, 4 and 5, as shown in 95 Figure 1.

Steam enters the valve 9, from the steam line 19, through the ports 21 and 17 and when the valve port 31 registers with the pipe 34 the steam will pass into the expansion chamber of the cylinder 5. As the valve continues to rotate the port 31 will pass out of registration with said steam pipe and the exhaust groove 18 will come into registration therewith and the spent steam will return through the pipe 34, the grooves 18, and 16 and will be exhausted through the exhaust pipe 20. Meanwhile the steam port 30 will have registered with the steam pipe 33 and steam will be delivered into the expansion chamber of the cylinder 4 and when the groove 18 registers with said pipe 33 the

spent steam will be exhausted from said last mentioned cylinder. And so on, the steam will be delivered to and exhausted from said cylinders, in succession through the pipes 5 32, 33 and 34, each pipe alternately delivering steam to and exhausting it from its corresponding cylinder.

It is to be observed that the valve sleeve controls the passage of steam through the 10 valve to the steam pipes 32, 33 and 34. This sleeve may be adjusted so that the forward ports 23, 24 and 25 will be in position to register with the corresponding valve ports 29, 30 and 31 and the engine will be driven 15 forwardly. To reverse the engine the valve sleeve may be adjusted, through the lever 13, so that the reverse ports 26, 27 and 28 will register with the corresponding valve ports and the engine will be reversed. The valve 20 sleeve ports are correspondingly tapered, as above explained, so that the path of travel of the valve ports across them may be lengthened, or shortened, and the amount of steam delivered to the cylinders thus controlled by 25 a suitable shifting of the valve sleeve.

In the form shown in Figures 6 to 11 inclusive, provision is made for delivering steam to, and exhausting it from, opposite sides of the pistons 6. In this form the 30 steam pipes 35, 36 and 37 lead from one side of the casing 11' and communicate with the respective cylinders 3, 4 and 5 between the pistons 6 and the cylinder heads, and the steam pipes 38, 39 and 40 lead from the opposite sides of the casing 11' and communicate with said respective cylinders 3, 4 and 5 on the other sides of the pistons 6. The valve sleeve, in this form, has two series of forward ports, 23' 24' and 25', as well as 40 two series of reverse ports, 26' 27' and 28', oppositely arranged so as to register alternately with the respective steam pipes of the two series, 37, 36, and 35, and 38, 39, and 40, of pipes. In the other respects this 45 form of the engine is similar to that shown in Figures 1 to 5, inclusive, and hereinabove described.

What I claim is:—

1. In an engine a hollow rotary valve, 50 provided with a steam inlet port in constant communication with an inlet steam line and also provided with an outlet port and a spiralled exhaust passageway, a valve sleeve around said valve provided with an outlet 55 port, said sleeve port alternately registering with said valve outlet port and exhaust passageway.

2. In an engine a valve casing, a slidable sleeve therein, a hollow rotary valve in the 60 sleeve, an inlet steam line entering the casing, an exhaust line leading from the casing, said valve having a steam inlet passageway in constant registration with said inlet line, and a spiralled exhaust passageway in 65 constant registration with said exhaust line,

said sleeve having inlet and exhaust ports adapted to be brought into and out of registration with said inlet and exhaust lines respectively, said valve and sleeve, each, also having an outlet port, said sleeve outlet port being arranged to register alternately with the valve outlet port and spiralled exhaust 70 passageway.

3. In an engine, a valve casing, a slidable sleeve therein, formed with oblong end 75 ports, a hollow rotary valve in the sleeve, formed with annular end grooves communicating with said end ports, one of said grooves having inlet ports, leading into the interior of the valve, an inlet steam line entering the casing, an exhaust line leading from the casing, said inlet and exhaust lines being in constant communication with said grooves, a spiralled exhaust groove around 80 said valve in constant communication with said exhaust line, through one of said end grooves, said valve and sleeve each also having an outlet port, said outlet port of said sleeve being arranged to register alternately with the valve outlet port and exhaust passageway, and means for shifting the sleeve 85 lengthwise relative to the valve.

4. An engine including a plurality of cylinders, a crank shaft, pistons in said cylinders operatively connected to the crank shaft, steam conduits entering the expansion chambers of the respective cylinders, means controlling said conduits and formed to alternately admit steam into and exhaust it from said chambers in succession, said means including a valve casing, a sliding sleeve therein, a hollow rotary valve in the sleeve, an inlet steam line entering the casing, an exhaust line leading from the casing, said valve having a steam inlet passageway in constant registration with said inlet line, and a spiralled exhaust passageway in 100 constant registration with said exhaust line, said sleeve having inlet and exhaust ports adapted to be brought into and out of registration with said inlet and exhaust lines, respectively, said valve and sleeve each also having an outlet port, said sleeve outlet port being arranged to register alternately with the valve outlet port, and spiralled exhaust 105 passageway.

5. An engine including a plurality of cylinders, a crank shaft, pistons in said cylinders operatively connected to the crank shaft, steam conduits entering the expansion chambers of the respective cylinders, means controlling said conduits and formed to alternately admit steam into and exhaust it from said chambers in succession, said means including a valve casing, a sliding sleeve therein, a hollow rotary valve in the sleeve, an inlet steam line entering the casing, an exhaust line leading from the casing, said valve having a steam inlet passageway in constant registration with said inlet 120 line, and a spiralled exhaust passageway in constant registration with said exhaust line, 125 respectively, said valve and sleeve each also having an outlet port, said sleeve outlet port being arranged to register alternately with the valve outlet port, and spiralled exhaust 130 passageway.

line, and a spiralled exhaust passageway in constant registration with said exhaust line, said sleeve having inlet and exhaust ports adapted to be brought into and out of registration with said inlet and exhaust lines, respectively, said valve and sleeve each also having an outlet port, said sleeve outlet port being arranged to register alternately with the valve outlet port, and spiralled exhaust

passageway, and means for shifting the sleeve lengthwise relative to the valve.

In testimony whereof I have signed my name to this specification in the presence of two subscribing witnesses.

JAMES B. BURKS.
